UNITED STATES PATENT OFFICE.

CHARLES N. CLARK, OF SOMERVILLE, MASSACHUSETTS.

WAGON.

Application filed April 26, 1920. Serial No. 376,600.

To all whom it may concern:

Be it known that I, CHARLES N. CLARK, a citizen of the United States, residing in Somerville, county of Middlesex, and State of Massachusetts, have invented an Improvement in Wagons, of which the following description, in connection with the accompanying drawings, is a specification, like characters on the drawings representing like parts.

10 This invention relates to wagons of the character employed for delivering coal, gravel and like material and more particularly to wagons having a tail board or end gate which is capable of being moved into 15 a shoveling position or into a dumping position.

The present invention has for its object to provide a tail board which is pivoted at its upper and lower ends and is operatively 20 connected with the wagon body so as to be capable of being moved from both of its open positions into its closed position by mechanical means, as will be described.

25 The invention also has for its object to provide a simple, inexpensive and efficient construction of tail board of the character described.

The invention further has for its object to provide the tail board with a novel construction of guiding members for coal, as 30 will be described.

These and other features of the invention will be pointed out in the claims at the end of this specification.

35 Fig. 1 is a side elevation of a sufficient portion of a coal wagon embodying this invention, to enable the latter to be understood.

Fig. 2, a detail of the lower pivot for the 40 tail board.

Fig. 3, a view like Fig. 1 with the tail board in its horizontal or shoveling position.

Fig. 4, a view like Fig. 1 with the tail board in its dumping position.

45 Fig. 5, a rear elevation of the tail board shown in Fig. 1 with the sliding cover in its raised position.

Fig. 6, a detail of the upper pivot for the tail board.

50 Fig. 7, a section on the line 7—7, Fig. 5, and

Fig. 8, a detail of the sliding cover and wings to be referred to.

Referring to the drawing, 10 represents 55 the wagon body which may be of any suitable or usual construction, and 12 the tail

board or end gate therefor. The tail board 12 as herein shown is pivoted at its upper and lower ends, the pivot for the upper end being shown as a rotatable shaft or rod 13 extended through a suitable hole in the tail board and provided at its opposite ends with cranks 14, 15, which in the normal or closed position of the tail board hook over pins or lug 16, 17, carried by the sides of the wagon body 10. The crank or arm 15 cooperates with a spring member 18 attached to wagon body 10 so as to frictionally hold the cranks 14, 15 in locking engagement with the pins 16, 17 against accidental disengagement, while permitting them to be readily disengaged by the operator turning the shaft 13 in the proper direction through a handle 19 on the crank 15, when it is desired to lower the tail board 12 into a horizontal or shoveling position shown in Fig. 3.

The tail board 12 is provided at its lower end with a pivot shaft or rod 20, which is normally supported in bearings, shown as hooks or bent rods or arms 21 projecting radially from a shaft 22 rotatably mounted in bearings, shown as staples or eyes 23 attached to the wagon body 10.

The rotatable shaft 22 is provided at one end with a substantially long crank or arm 24, by means of which the operator can turn the shaft 22 so as to lower the hooks or bearings 21 from the pivot rod 20, see Fig. 4, and thus disconnect the lower end of the tail board from the wagon body, to allow the operator to turn the tail board on its upper pivot 13 and move its lower end away from the wagon body into its dumping position shown in Fig. 4, in which position an opening is afforded for the passage of the coal out of the wagon body especially when the front end thereof is lifted.

Provision is made for closing the opening referred to at the opposite sides of the tail board for a substantial distance above the latter, so as to avoid lateral displacement of the coal. To this end, the tail board has connected with it at each side thereof a closure member or side wall 25. Each closure member is preferably made as substantially a quadrant of a circle and is provided with a substantially horizontal bottom edge 26, a substantially vertical outer edge 27 and a curved edge 28. The closure member is loosely mounted on the lower pivot 20 for the tail board, and is connected with the tail board by a pin and slot con-

nection, a bent pin 30 affixed to the tail board being extended through a curved slot 31 in the closure member 25, the pivot 20 constituting the center for the curved slot 31. This pin and slot connection allows the tail board to be moved outward from its closed or vertical position shown in Fig. 1, into its open or inclined position shown in Fig. 4, with the side closure members 25 10 movable in a substantially straight direction with the front or free end of said closure member sliding across and being supported by the shaft 22.

Provision is made for moving the tail board into its closed position from its open shoveling position and from its open dumping position, with a minimum effort on the part of the operator. To this end, the closure members 25 on opposite sides of the tail board are connected to a windlass or rotatable shaft 40 extended transversely under the wagon body and suitably supported therefrom. The shaft 40 is preferably connected with the closure members 25 by 20 chains 41, which are shown as engaged with hooks 42 attached to said closure members. 25

The shaft 40 is provided with a handle 43 for turning it and with a ratchet wheel 44 with which cooperates a holding pawl 30 45 pivoted to the wagon body.

Provision is also made for sustaining the tail board and the weight of the coal thereon when said tail board is in its shoveling position. To this end each closure member 25 35 has attached to it a hooked member 46, which is arranged thereon so as to automatically engage a holding member 47 rigidly secured to the side of the wagon body and provided with a suitable eye (not 40 shown) which lies in the path of movement of the hooked member 46 and is engaged thereby when the tail board is in its shoveling position, see Fig. 3, and from which said hooked member is automatically disengaged 45 when the windlass is turned to wind the chains 41 thereon.

Provision is also made for retaining the bearing members 21 for the pivot 20 of the tail board in operative relation with the 50 latter against accidental disengagement. To this end, the wagon body 10 has secured to it a spring member 50 between the outer end of which and the wagon body, the free end of the crank or arm 24 is normally 55 placed. The crank or arm 24 possesses sufficient spring to enable it to be moved downward sufficiently to remove it from engagement with the spring member 50, when it is desired to move the crank or arm 24 60 up into the position shown in Fig. 4, and thereby release the pivot 20 of the tail board.

The tail board may and preferably will be provided with the usual opening 52, see Fig. 5, through which the coal may be 65 discharged with the tail board in its closed

position shown in Fig. 1, and with a sliding cover 53 for said opening. Provision is made for preventing the coal from spreading out laterally and for directing it into a basket or other receptacle placed in line with said opening, whereby loss of coal and the labor and time of cleaning up the sidewalk or driveway after the coal has been delivered may be reduced to a minimum. To this end, the tail board is provided with 70 wings or movable guiding members 54, which are mounted to turn on stationary vertical pivot rods 55, and which are provided with curved upper surfaces 56 suitably shaped to have a cam action and which 75 cooperate with the lower edge of the sliding cover 53, so that when the said cover is moved downward to close the opening 52, the lower edge of said cover will slide over the upper curved surface 56 and will turn the coal guiding members 54 on their pivots from their open position represented in Fig. 80 7 into their closed position, in which they extend across the opening 52 substantially in the plane of the tail board. The sliding cover 53 is movable between vertical guides 85 58 and may be moved by a lever 59 in a manner well understood.

From the above description, it will be seen that while the load is in transit, the 90 tail board is in its closed position shown in Fig. 1 and is held in this position by the holding pawl 45 of the windlass.

When it is desired to shovel the load from the wagon, the tail board is moved into its 100 horizontal position shown in Fig. 3, which is effected by the operator throwing back the holding pawl 45, and rotating the upper pivot or shaft 13 to release the upper end of the tail board, which leaves the latter free to be turned down by gravity, assisted 105 it may be by the operator until the hooked members 46 engage the stops or sustaining members 47, as shown in Fig. 3. If it is desired to dump the coal, the handle or crank 24 is disengaged from its holding member 50 and turned up into the position shown in Fig. 4, so as to release the tail board at its lower end, which is then pushed 110 out by the load into the position shown in Fig. 4.

One embodiment of the invention is herein shown, but it is not desired to limit the invention to the particular construction shown.

From the above description, it will be seen that a single operator from one side of the wagon can control the tail board so that it can be placed into a shoveling position or into a dumping position as he desires and can close the tail board from either position and lock it in its closed position.

The pin and slot connection 30, 31, is preferably arranged so that the pin 30 is made shorter than the length of slot 31 and is ca- 130

pable of being turned into alignment with the slot so as to permit the side closure members 25 to be sprung laterally and disengaged from the pins 30, and thereby leave the tail board, when released at its upper end, to be turned down into a substantially vertical position on the pivot 20, when it is desired to load the wagon body by shoveling from the ground.

10 Claims:

1. The combination with a wagon body, of a tail board pivotally secured thereto at its upper and lower ends, means for detachably securing said pivoted upper and lower ends 15 to said wagon body, side closure members pivotally secured to the lower end of said tail board, a windlass carried by the wagon body and connected with said closure members to close the tail board from both open 20 positions, stop members secured to said wagon body, and means on said side closure members for engaging said stop members.

2. The combination with a wagon body, of a tail board pivotally secured thereto at its 25 upper and lower ends, means for detachably securing said pivoted upper and lower ends to said wagon body, side closure members pivotally secured to the lower end of said tail board, and a windlass carried by the 30 wagon body and connected with said side closure members to move the tail board from both of its open positions into its closed position.

3. The combination with a wagon body, 35 of a tail board pivotally secured thereto at its upper and lower ends, means for detach-

ably securing said pivoted upper and lower ends to said wagon body, side closure members pivotally secured to the lower end of said tail board, and mechanical means carried by 40 said wagon body and operatively connected with said side closure members to move the tail board from both of its open positions into its closed position.

4. The combination with a wagon body, of 45 a tail board cooperating therewith, upper and lower pivots for said tail board carried by said tail board, means on the wagon body co-operating with the upper pivot to secure the latter to the wagon body, side closure members co-operating with said tail board and wagon body and in which the lower pivot for the tail board is mounted, means for connecting the side closure member with the tail board to permit the latter to turn on the 50 lower pivot and be moved with respect to said side closure members, and means carried by said wagon body for detachably supporting the lower pivot for the tail board.

5. The combination with a wagon body, of 55 a tail board or end gate therefor provided with an opening for the discharge of the contents of the wagon body, pivoted side guides for said contents cooperating with said opening, and a slide to cover said opening cooperating with said side guides to automatically turn the same from their operative into their inoperative position, when said slide is moved to close said opening.

In testimony whereof, I have signed my 70 name to this specification.

CHARLES N. CLARK.
